UNITED STATES PATENT OFFICE

154,595

DESIGN FOR A VENETIAN BLIND CLEANER

Livio Franchi, Cicero, Ill.

Application September 4, 1948, Serial No. 148,485

Term of patent 7 years

(Cl. D9—2)

To all whom it may concern:

Be it known that I, Livio Franchi, a citizen of the United States, residing in the village of Cicero, county of Cook, and State of Illinois, have invented a new, original, and ornamental Design for a Venetian Blind Cleaner, of which the following is a specification, reference being had to the accompanying drawing, forming a part thereof.

I claim:

The ornamental design for a Venetian blind cleaner, substantially as shown.

LIVIO FRANCHI.
